Primary Examiner — Jennifer L Rempfer*Assistant Examiner* — Aaron C Fowler(74) *Attorney, Agent, or Firm* — ADAMS IP, LLC; James Adams; Edward Garner(57) **CLAIM**

The ornamental design for a ferry boat, as shown and described.

DESCRIPTION

FIG. 1 is a front view of a ferry boat showing the claimed design;

FIG. 2 is a back view thereof;

FIG. 3 is a left side view thereof;

FIG. 4 is a right side view thereof;

FIG. 5 is a top view thereof;

FIG. 6 is a bottom view thereof; and,

FIG. 7 is an elevated front left perspective view thereof.

The broken lines in the figures show portions of the ferry boat subject matter that form no part of the claimed design.

1 Claim, 6 Drawing Sheets(56)
